CLAIM

The ornamental design for an oral care organizer, as shown and described herein.

DESCRIPTION

FIG. 1 is a front, top, right side perspective view of an oral care organizer in accordance with an embodiment of the present design.

FIG. 2 is a rear, top, right side perspective view of the oral care organizer shown in FIG. 1.

FIG. 3 is a front view of the oral care organizer shown in FIG. 1.

FIG. 4 is a rear view of the oral care organizer shown in FIG. 1.

FIG. 5 is a left side plan view of the oral care organizer shown in FIG. 1.

FIG. 6 is a right side plan view of the oral care organizer shown in FIG. 1.

FIG. 7 is a top side plan view of the oral care organizer shown in FIG. 1; and,

FIG. 8 is a bottom side plan view of the oral care organizer shown in FIG. 1.

The broken lines in the drawings illustrate portions of the oral care organizer that form no part of the claimed design.

1 Claim, 8 Drawing Sheets
